UNITED STATES PATENT OFFICE

104,830

DESIGN FOR A GLOVE

Brenton F. Beverly, New York, N. Y.

Application April 9, 1937, Serial No. 68,651

Term of patent 7 years

To all whom it may concern:

Be it known that I, Brenton F. Beverly, a citizen of the United States of America, residing in Manhattan, county of New York, and State of New York, have invented a new, original, and ornamental Design for a Glove, of which the following is a specification, reference being had to the accompanying drawing, forming part thereof, wherein,

I claim:

The ornamental design for a glove, substantially as shown.

BRENTON F. BEVERLY.
